CLAIM

The ornamental design for a physical therapy apparatus, substantially as shown and described.

DESCRIPTION

FIG. 1 is a front left perspective view of a physical therapy apparatus according to an embodiment of the design.

FIG. 2 is a front right perspective view of the design of FIG. 1.

FIG. 3 is a rear right perspective view of the design of FIG. 1.

FIG. 4 is a rear left perspective view of the design of FIG. 1.

FIG. 5 is a front end view of the design of FIG. 1.

FIG. 6 is a rear end view of the design of FIG. 1.

FIG. 7 is a right side view of the design of FIG. 1.

FIG. 8 is a left side view of the design of FIG. 1.

FIG. 9 is a top view of the design of FIG. 1.

FIG. 10 is a bottom view of the design of FIG. 1.

FIG. 11 is a front right perspective view of the design of FIG. 1 shown in a folded state; and,

FIG. 12 is a right side view of the design of FIG. 1 shown in a folded state.

The broken lines are included for the purpose of illustrating portions of the physical therapy apparatus that forms no part of the claimed design.

1 Claim, 10 Drawing Sheets
